(57) **CLAIM**

The ornamental design for a combined eyeglasses and camera, as shown and described.

DESCRIPTION

FIG. 1 is a front perspective view of the combined eyeglasses and camera of an embodiment of the present invention;

FIG. 2 is a front elevational view of the combined eyeglasses and camera of the embodiment of FIG. 1;

FIG. 3 is a rear elevational view of the combined eyeglasses and camera of the embodiment of FIG. 1;

FIG. 4 is a right-side elevational view of the combined eyeglasses and camera of the embodiment of FIG. 1;

FIG. 5 is a left-side elevational view of the combined eyeglasses and camera of the embodiment of FIG. 1;

FIG. 6 is a top plan view of the combined eyeglasses and camera of the embodiment of FIG. 1;

FIG. 7 is a bottom plan view of the combined eyeglasses and camera of the embodiment of FIG. 1;

FIG. 8 is a back perspective view of the combined eyeglasses and camera of the embodiment of FIG. 1;

FIG. 9 is a another perspective view of the combined eyeglasses and camera of the embodiment of FIG. 1 with an arm folded in; and,

FIG. 10 is an enlarged view of an indicated portion of FIG. 9.

The dot-dash broken lines encircling enlargement portions of the design form no part of the claimed design.

The dashed broken line portions of the combined eyeglasses and camera in FIGS. 9-10 represent unclaimed portions of the claimed design and form no part thereof.

1 Claim, 10 Drawing Sheets
